UNITED STATES PATENT OFFICE.

HARRY D. CAYLOR AND WILLIAM A. SCOTT, OF INDIANAPOLIS, INDIANA, ASSIGNEES
TO NATIONAL CONING MACHINERY COMPANY, OF INDIANAPOLIS, INDIANA, A
CORPORATION OF INDIANA.

SHEET-FEEDING MECHANISM.

1,147,308.

Specification of Letters Patent. Patented July 20, 1915.

Original application filed October 18, 1913, Serial No. 796,059. Divided and this application filed September 28, 1914. Serial No. 863,884.

To all whom it may concern:

Be it known that we, HARRY D. CAYLOR and WILLIAM ALLISON SCOTT, citizens of the United States, residing at Indianapolis, in 5 the county of Marion and State of Indiana, have invented certain new and useful Improvements in Sheet-Feeding Mechanism, of which the following is a specification.

This invention is a division out of our 10 application for patent for machine for making paper vessels, Serial No. 796,059, filed October 18, 1913, and relates to means for transferring the paper blanks.

The object of the invention is to provide 15 a machine with a receptacle within which blanks of the desired and required shape and material are placed, and which will automatically feed the blanks in proper position to the bottom of the receptacle and then automatically, separately and successively take 20 the blanks from the bottom of the pile through the bottom of the receptacle and transfer it away from the receptacle.

We accomplish the above and other objects 25 which will hereinafter appear by the mechanism illustrated in the accompanying drawings, in which—

Figure 1 is a top plan view of our invention. Fig. 2 is a front elevation of same. 30 Fig. 3 is a fragment in top plan view, on a larger scale, of that portion of the machine where the paper blank is handled in its flat condition and positioned to be bent into conical form around a mandrel which is shown in 35 dotted lines, portions of the superimposed structure being broken away to show the underlying parts. Fig. 4 is a continuation of Fig. 3 on the same scale, showing the mandrel in dotted lines around which the 0 truncated conical bodies are formed. Fig. 5 is a vertical section of the second suction head and its associated parts, taken on the line 7—7 of Fig. 15. Fig. 6 is a vertical section on the line 8—8 of Fig. 3, and shows 5 the mechanism in elevation for raising and lowering the suction head which takes the blanks from the receptacles seriatim and for moving the head horizontally to its transfer position. Fig. 7 is a side elevation of the cam-wheel shown at the bottom of Fig. 6, illustrating the opposite side of the wheel from that shown in Fig. 6. Fig. 8 is a vertical section through the receptacle and suc-

tion head transversely of the head with the head in position at the bottom of the receptacle to remove a blank. Fig. 9 is a vertical section on the line 11—11 of Fig. 3, showing the assembly of the suction head shown in Fig. 6, with the carriage by which it is supported and showing the three-way 60 valve which controls the suction. Fig. 10 is a detail in side elevation of the mechanism connected with the same lever which controls the movement of the suction head shown in Fig. 6 for automatically operating 65 the valve which controls the supply of air to the suction head. Fig. 11 is a horizontal section on the line 13—13 of Fig. 10, showing the same parts in top plan view as are illustrated in elevation in Fig. 10. Fig. 12 70 is a section on the line 14—14 of Fig. 11, and illustrates the spring mechanism located within the hollow horizontal shaft of this device. Fig. 13 is a fragment in top plan view showing the tracks and the sliding 75 carriage thereon from which the second suction head is suspended. Fig. 14 is a side elevation of the same parts showing the second suction head depending from the carriage and showing the first suction head 80 in dotted lines under the second one, in position to transfer a blank. Fig. 15 is a section on the line 17—17 of Fig. 14, showing the sliding carriage and second suction head 85 in elevation. Fig. 16 is a section on the line 18—18 of Fig. 14, showing the sliding carriage and second suction head in elevation.

Like characters of reference indicate like parts throughout the several views of the drawings.

The main frame of the machine is indicated at 5 and 6 is one of the principal driving shafts of the machine.

Referring to Figs. 1, 2 and 10, a hopper 2 is shown in which flat blanks of tag-board, 95 or other suitable paper material previously cut to the required size and shape are placed. The tapering sides of the hopper direct the blanks which may be more or less irregularly stacked, into proper position at the bottom of the hopper to be removed one at a time through an opening in said bottom by a suction head 3. This head is hollow and its top plate is perforated, and in order to cause the blanks to be separated and removed one at a time we curve this perfor-

rated plate in the direction of a medial line between the straight edges of the blank to be removed. This causes a blank to be drawn down at its straight edges below its middle portion by a suction thereby detaching the bottom blank at each visit of the suction head to the hopper, from the ones above. The suction head 3 is supported by an integral sleeve 7 which is mounted telescopically on a pipe 8 extending up vertically from a tubular carriage 9. The tubular carriage 9 slides telescopically on a pipe 10. (See Figs. 2 and 9.) The pipe 10 is horizontal and connects with a vertical pipe 11 through an elbow which contains a three-way valve 12 adapted to form communication between the two pipes 10 and 11, and to atmosphere, to enable the vacuum in the head 3 to be controlled, and also to be broken for the quick release of a blank. The automatic control of the valve will be hereinafter described. The downward travel of the head 3 is limited by the contact of its sleeve 7 with a shoulder 13, (see Fig. 6), on the carriage 9, and the lowering of the head is quickened and made more positive by a spring 14, the spring being wrapped around the rod 14' between a head on the end of the rod and a lug on the carriage 9.

30 Mounted on an extension of the carriage 9 is a bell-crank lever, the upper end of which has a toothed segment 16 which engages with a rack carried by the sleeve 7. The lower arm of the bell-crank lever is connected by a link 17 with the upper end of a long bent lever 18 fulcrumed to a bracket from the frame of the machine. The lever 18 is oscillated to first raise or lower the head and then move the carriage 40 on the pipe 10, by connection with a cam in the wheel 19 on the shaft 6; and, on account of the conical shape of the finished product requiring the blanks to be glued in a plane at less than a right angle to the longitudinal axis of the cone-carrying mandrels on which the blanks are folded and on which the construction of the bottle is continued, we provide a connection between the lever 18 and cam wheel 19 which partakes of the 50 functions of a swivel and of a universal joint. A pin entering the cam-slot in wheel 19 is carried by a lever 20 which has a lower bifurcated end straddling the shaft 6 to prevent displacement. The upper end of lever 20 is hinged to a rod 21. The rod 21 is in two parts which are connected by a swivel 22. The upper end of the rod is bifurcated and pivoted in the fork is a journal box 23 in which the pivot pin connecting the foregoing structure with the short arm of lever 18, is journaled.

60 After the suction head 3 has removed a paper blank from the hopper the head is moved by the sliding of the carriage 9 in pipe 10 to a position under the suction head

4 as shown in dotted lines in Fig. 14. The blank is released from the head 3 by changing the position of the valve on the elbow between pipes 10 and 11, permitting air to enter through the pipe 10. The mechanism for automatically opening the valve is illustrated in Figs. 9 to 12 inclusive. An arm on the valve stem is connected by rod 24 with an arm on a lower horizontal barrel 25, which arm is secured thereto by means of a set-screw, so they will rock together. A lever 26 is loosely mounted on the barrel 25 and is connected by a link bar 27 with the lever 18. Secured at one end to the hub of the lever 26 and at the other to the barrel 25 within the latter at a suitable distance from the hub, is a torsion spring 28 the purpose of which is to impart the required potential energy to the barrel when the latter is released to cause its arm, acting through the rod 24, to throw the valve between the pipes 10 and 11 quickly.

Mounted in a fixed manner on the barrel are two notched disks 29 and 30, and supported from the frame of the machine by brackets are latches 31 and 32, which are alternately in engagement with the notch of a corresponding one of the disks 29 and 30. The latches are drawn toward each other by a spring 33 and one of them is held out of contact with its notched disk by a pin 34, passing through an extension below the barrel of the lever 26. A throw of the lever 18 will release the barrel 25 by releasing one of the latches 31 or 32, and the latch previously out of engagement will immediately lock the shaft so a return movement of the lever 18 will stress the spring 28 for an opposite throw of the valve when the latch is correspondingly released. This valve mechanism is so timed that when the head 3 has reached a position under the head 4, by the action of the lever 18, the suction in head 3 will be removed coincident with the blank being picked up by the head 4.

After the head 4 has obtained possession of the paper blank delivered to it by the head 3 it subjects the blank to the mechanism for applying glue to one of its edges and then delivers the blank to the mechanism for folding it into conical form and retains possession until it is seized by pilot pins and held in position on a mandrel ready for the folding mechanism to act. The head 4 is suspended from a carriage 35 which has a reciprocating travel on track rails 36. The carriage passes the glue wheel 37 which is located between the rails 36. Travel is imparted to the carriage by the connection through rod 38 with a horizontal rotating arm 39 on a vertical rotating shaft 40. (See Figs. 1 and 4.) The bottom perforated plate of the head 4 is hinged at one end, the hinge pin being at right angles to the axis of the mandrel on which

it deposits its blank. The purpose of this is to allow the perforated plate to change from a horizontal position to an angular one parallel with the adjacent side of the 5 mandrel after it has reached the latter with a paper blank. This swinging of the plate is caused by a rod 285 (see Figs. 13, 14 and 5) which passes through the head and is connected by a link with the perforated 10 plate. A roller on the other end of the rod contacts with a cam 286 (see Figs. 1, 2 and 3) which lowers the rod by a longitudinal movement of the latter. The edges of the 15 perforated plate and head 4 are connected by a bellows 288. The air in the head 4 is exhausted through a pipe 42, which telescopes in a pipe 43, the latter being connected with a suitable exhaust not shown, and located in pipe 42 is a three-way valve 44, 20 (see Fig. 5), similar in construction and function to the three-way valve between pipes 10 and 11.

Mounted upon the carriage 35 is a barrel similar to barrel 25 already described, with 25 in which is the same construction of torsion spring as 28. A lever 45 secured to the outer end of the torsion spring is thrown by contact with trips, here shown as rollers 46, secured to a rail of the track at the desired points. The notched disks 29 and 30 are engaged by latch bars 47 and 48, pivoted to the carriage and pressed into contact with the disks by springs 50, shown in dotted lines in Fig. 14. The notches in the 35 disks are placed so that only one latch will be in engagement at a time. The release will be by contact of the outer ends of the levers with trips 51 (see Fig. 4) secured to a rail. The trips will be located at proper 40 points to open and close the valve at the right times.

We claim:—

1. In a machine for the manufacture of paper vessels, the combination of a holder 45 for blanks to form the sides of the vessel having a bottom discharge opening and sides tapering toward said bottom opening, a suction head adapted to move through the opening in the bottom of the holder into contact 50 with the bottom blank and withdraw it by suction and the downward travel of the head, the top plate of said head being curved and perforated at intervals of its entire surface and the highest portion of the 55 head being midway of the tapering sides of the holder to center the blank on the head.

2. In a machine for the manufacture of paper vessels, the combination of a holder for blanks to form the sides of the vessel, 60 suction means for taking such blanks one at a time through the bottom of the holder, means for transferring the blank taken from the bottom of the holder and suction means for securing the blank to said transferring 65 means.

3. In a machine for the manufacture of paper vessels, the combination of a holder for blanks to form the sides of the vessel having a discharge opening through its bottom, a suction head adapted to move through 70 the opening in the bottom of the holder into contact with the bottom blank and withdraw it by suction and the downward travel of the head, the top plate of said head being perforated and lower at its edges than at intermediate portions and lower portions being 75 also perforated.

4. In a machine for the manufacture of paper vessels, the combination of a hopper-shaped holder in which blanks to form the 80 sides of the vessel are stacked, said holder having its discharge opening in its bottom, a suction head having vertical reciprocating movement through the bottom opening in the hopper, the plate of the head coming 85 closest to the blanks when the head is in the hopper being perforated and also raised above the edges of the plate along the medial line between the straight edges of the blank. 90

5. In a machine for the manufacture of paper vessels, the combination of a holder for blanks to form the sides of the vessels having a discharge through its bottom for 95 said blanks, a suction head adapted to act upon the middle of the lowest blank and withdraw it singly from the holder, a second suction head acting upon the opposite side of the blank at one side of the middle after it has been withdrawn from the holder, means to cause the first suction head to release the blank when the second one takes it, means to move the second suction head to the place of discharge of the blank, and means to discharge the blank. 100

6. In a machine for the manufacture of paper vessels, the combination of a holder for the blanks to form the sides of the vessel, a suction head to draw blanks one at a time out of the holder and acting upon the middle 110 of the blank, a second suction head acting at one side of the middle and on the opposite side of the blank after it has been withdrawn from the holder by the first head, means destroying the vacuum to cause the 115 first suction head to release the blank when the second one takes it, means to move the second suction head to the place of deposit of the blank, and means destroying the 120 vacuum in the second head to release the blank. 125

7. In a machine for the manufacture of paper vessels, a holder containing a supply of blanks, a reciprocating suction head for taking one blank at a time from said holder, 130 and a second suction head reciprocating in a different plane, which second head takes the blank from the first head by contact with the opposite side of the blank and transfers it. 135

8. In a machine for the manufacture of paper vessels, a holder containing a supply of blanks, a reciprocating suction head for taking one blank at a time from said holder through its bottom, a second reciprocating suction head which takes the blanks from the first head by contact with the opposite side of the blank and transfers it, pipes connected with said heads through which air is exhausted, and valves in said pipes to open and close communication through the pipes and also from the interior of the pipes to atmosphere.

9. In a machine for the manufacture of paper vessels, a holder containing a supply of blanks, a reciprocating suction head for taking one blank at a time from said holder through its bottom, a second reciprocating suction head to which the blank is transferred by the first suction head, and means to break the suction in the first head coincident with the taking hold of the blank by suction by the second head.

10. In a machine for the manufacture of paper vessels, a holder containing a supply of blanks, a reciprocating suction head for taking one blank at a time from said holder through its bottom, a second reciprocating suction head which takes the blank from the first head and transfers it, telescoping pipes through which air is exhausted from the respective heads, valves in said pipes controlling the passage of air therethrough and also providing communication to atmosphere, means to move the first head to the blank holder of the second head, automatic means to operate the valve and break the suction to the first head when in position to transfer its blank to the second head, means to move the second head into position to transfer its blank, and means to operate its valve and break the suction in the head to release the blank to said forming means.

11. In a machine for the purposes specified, suction heads for taking body blanks one at a time and transferring them, pipes connected with an exhaust means and with said heads, valves in said pipes having stems and arms, a rocking barrel, a lever loosely mounted on the barrel, a torsion spring connected at one end to the hub of said last lever and at the other end to the interior of the barrel, a rod connecting the last lever with the arm on a valve, means for moving the suction heads to transfer the blanks, pawl and ratchet means to hold the tension of the torsion spring in the barrel, and means connected with the means for moving the suction heads to move the pawls in a manner to release said ratchet means and spring.

12. In a machine for the purposes specified, suction heads for taking body blanks one at a time and transferring them, air exhaust pipes in telescoping sections on one of

which a head is mounted, a valve in the pipes to each head having a stem and an arm, head transferring means, a rocking barrel connected with said valve arm, a lever mounted loosely on the barrel and connected with said head transferring means, a pair of notched disks mounted on the barrel, a latch bar for each disk, springs to press the latch bars into normal engagement with their respective disks, means by the rocking of the barrel for alternately releasing said disks, and a torsion spring connected at one end with the interior of the barrel and at the other end with said lever mounted loosely on the barrel.

13. In a machine for the manufacture of paper vessels, a receptacle holding paper blanks from which the vessels are formed, said receptacle having a bottom opening, a suction pipe extending under the receptacle, a hollow carriage telescopically mounted on said pipe, a pipe extending vertically from the carriage, a sleeve mounted telescopically upon said last pipe, a suction head on the upper end of the sleeve, and means for moving the carriage so the head will be under the bottom opening in said receptacle and for then raising and lowering the head to remove a blank.

14. In a machine for the manufacture of paper vessels, a receptacle holding paper blanks, said receptacle having a bottom opening, a suction pipe extending under the receptacle, a hollow carriage telescopically mounted on said pipe, a vertical pipe extension from the carriage, a sleeve telescopically mounted on the vertical pipe extension, a suction head on the upper end of the sleeve, a vertical rack on the sleeve, a bell-crank lever mounted on the carriage having a toothed segment on one arm engnging the rack on the sleeve, a bent lever pivoted to the frame of the machine, a link connecting the upper end of the last lever with said bell-crank lever, and cam means for moving the said bent lever.

15. In a machine for the manufacture of paper vessels, a receptacle holding paper blanks, said receptacle having a bottom opening, a suction pipe extending under the receptacle, a hollow carriage telescopically mounted on said pipe, a vertical pipe extension from the carriage, a sleeve telescopically mounted on the vertical pipe extension, a suction head on the upper end of the sleeve, a vertical rack on the sleeve, a lug on the sleeve, a lug on the carriage below the one on the sleeve, a rod fastened to the upper lug and passing through the lower one, an adjustable nut on the threaded lower end of the rod, a spring between said nut and said lower lug, a toothed segment engaging the rack on the sleeve said segment being mounted on the carriage, and means acting first through the toothed segment to move it to

85

the limit of its travel and then to move the carriage on its supporting pipe.

16. In a machine for the manufacture of paper vessels, a receptacle holding paper blanks, said receptacle having a bottom opening, a suction pipe extending under the receptacle, a valve in said pipe controlling a discharge through the pipe and also to atmosphere, a hollow carriage telescopically mounted on said pipe, a vertical pipe extension from the carriage, a sleeve telescopically mounted on the vertical pipe extension, a suction head on the upper end of the sleeve adapted to be brought into contact with the blanks through the bottom of the

receptacle, means to move the sleeve to the limit of its travel and then to move the carriage, means to operate the valve in the suction pipe, and means to operate said last means from the sleeve and carriage moving 20 means.

In witness whereof, we have hereunto set our hands and seals at Indianapolis, Indiana, this 21st day of March, A. D. one thousand nine hundred and fourteen.
